W. J. HINZE AND C. D. AND S. B. KATTERHEINRICH,

BRACKET,

APPLICATION FILED MAY 10, 1919.

1,326,731.

Patented Dec. 30, 1919.

UNITED STATES PATENT OFFICE.

WILLIAM JOHN HINZE, CHRISTY DANIEL KATTERHEINRICH, AND SAMUEL BENJAMIN KATTERHEINRICH, OF NEW KNOXVILLE, OHIO.

BRACKET.

1,326,731.

Specification of Letters Patent. Patented Dec. 30, 1919.

Application filed May 10, 1919. Serial No. 296,245.

To all whom it may concern:

Be it known that we, WILLIAM JOHN HINZE, CHRISTY DANIEL KATTERHEINRICH, and SAMUEL BENJAMIN KATTERHEINRICH, 5 citizens of the United States of America, residing at New Knoxville, in the county of Auglaize and State of Ohio, have invented certain and useful Improvements in Brackets, of which the following is a specification.

10 This invention relates to an improvement in brackets, and particularly to a bracket adapted for removable connection to the casing of a pump driven by wind mill or 15 hand to convert the pump into a constant power pump.

The invention broadly consists in the provision of a bracket, adapted for removable connection to the pump casing, and constructed to support a power shaft designed 20 for operation from an engine or the like, and arranged to be connected to the pump rod, whereby without change or the dismantling of any of the parts of the pump structure, 25 no matter how originally operated, the pump may be converted into a constant power pump.

In the drawings:—

Figure 1 is a perspective view illustrating 30 the application of the improvement.

Fig. 2 is an enlarged perspective of the bracket and power shaft.

The improved jack is designed for application to a pump casing, as 1, and to be 35 removably connected therewith at will, in order that the pump, as for example of the wind mill or hand driven type, may be readily converted into a constant power pump, to be operated, for example by an engine.

40 The improved bracket, which forms an essential feature of the present invention, comprises a base plate 2, of substantially uniform width for substantially half its length, and provided at approximately its mid 45 length point with an outstanding web 3, formed at its free end with elongated bearing 4. Beyond the web 3 the base plate proper is gradually reduced in width and 50 upwardly curved, terminating in an elongated bearing 5 in line with the bearing 4.

The relatively inner end of the base plate, that is the end remote from the bearing 5 is thickened, as at 6 to increase the strength 55 at this point, and is provided in the surface

from which the web 3 extends with a transversely extending channel 7, of a form to substantially interfit with the casing 1 of the pump. On opposite sides of the channel the base plate is formed with openings 60 8 through which are adapted to pass the lugs 9 of U-shape connectors 10, which embrace the case 1 in opposition to the bearing of the base plate, as seen in Fig. 1. Nuts 11 engage the free ends of the legs 65 9 beyond the base plate, to thus removably secure the bracket to the pump casing, in an obvious manner.

A power shaft 12 is rotatably mounted in the alined bearings 4 and 5, the inner 70 end of said shaft being provided with a crank 13, such crank end being adjacent the bearing 4. A pitman 14 is formed with an opening to engage the crank 13, the crank rod proper being preferably a removable 75 headed pin to provide for this connection of the pitman. The pitman is provided at the opposite end with a lateral extension, in the form of a pin 15, which is adapted to pass through an appropriate opening in 80 the pump rod 16, and to be secured against accidental disconnection by any appropriate means 17, of which the cotter pin illustrated is an example.

The end of the power shaft 12 remote 85 from the crank 13 is formed for the reception of a band or belt wheel 18, removably secured on said shaft by a set screw 19, and to be operated by belt or drive connection from a constant power unit, as a gas engine, 90 indicated at 20.

The base plate 2 is provided adjacent the web 3 with an eye 21, projecting from one edge of said plate, and adapted to receive a tie rod 22, preferably adjustable in order to 95 provide a connection from the bracket to the power plant if any of the commercial light power stands are used. This braces such power stand from the bracket and insures more even action.

100 It is apparent that the improved bracket may be readily and conveniently connected to a pump casing, and this without in any way interfering with or changing the construction or arrangement of the ordinary 105 pump parts. When in position the pump rod is operated directly by the power plant as will be obvious.

Claims:—

110 1. A bracket comprising a base plate

formed with a channel to receive the pump casing, a web projecting laterally from the base plate and terminally provided with a bearing, the base plate beyond the web being 5 of gradually reduced width and curved in the direction of the web projection, the free end of the base plate being provided with a bearing in alinement with the bearing on the web, and a power shaft mounted in said 10 bearing.

2. A bracket including a base plate formed with a channel extending throughout the full height thereof to partially receive a pump casing, means adapted to be

secured to the base plate for clamping the 15 latter to the casing, spaced bearing members projecting to one side of and beyond the base plate, one of said bearing members being projected from the base plate intermediate the ends thereof, and an operating shaft mounted in said bearing members. 20

In testimony whereof we affix our signatures.

WILLIAM JOHN HINZE.

CHRISTY DANIEL KATTERHEINRICH.

SAMUEL BENJAMIN KATTERHEINRICH.
